Patented June 2, 1959

185,379

FLOOR MAT FOR AUTOMOBILES AND THE LIKE

Emanuel Meyer, Philadelphia, Pa.

Application November 12, 1958, Serial No. 53,346

Term of patent 14 years

(Cl. D9—6)

Des. 185,379

PAGE 2

FIG. 2.

FIG. 4.

FIG. 3.

FIG. 5.

FIG. 6.

FIG. 7.

FIG. 8.

Fig. 1 is a top plan view of a floor mat for automobiles embodying my new design.

Fig. 2 is an enlarged fragmentary view of the portions of the mat enclosed within the broken line circles indicated by the references II in Fig. 1.

Fig. 3 is an enlarged fragmentary sectional view taken as indicated by the angled arrows III—III in Fig. 2.

Fig. 4 is an enlarged fragmentary view of the portions of the mat enclosed within the broken line circles indicated by the references IV in Fig. 1.

Fig. 5 is an enlarged fragmentary sectional view taken as indicated by the angled arrows V—V in Fig. 4.

Fig. 6 is an enlarged fragmentary view of the portions of the mat enclosed within the broken line circles indicated by the references VI in Fig. 1.

Fig. 7 is an enlarged fragmentary sectional view taken as indicated by the angled arrows VII—VII in Fig. 6.

Fig. 8 is an enlarged fragmentary sectional view taken as indicated by the angled arrows VIII—VIII in Fig. 6.

Fig. 9 is an enlarged fragmentary view of the portion of the mat enclosed within the broken line circle indicated by the reference IX in Fig. 1.

Fig. 10 is an enlarged fragmentary sectional view taken as indicated by the angled arrows X—X in Fig. 9.

Fig. 11 is an enlarged fragmentary sectional view taken as indicated by the angled arrows XI—XI in Fig. 9.

Fig. 12 is an enlarged fragmentary view of the portion of the mat enclosed within the broken line area indicated by the reference XII in Fig. 1.

Fig. 13 is an enlarged fragmentary view of the portion of the mat enclosed within the broken line circle indicated by the reference XIII in Fig. 1.

Fig. 14 is an enlarged fragmentary sectional view taken as indicated by the angled arrows XIV—XIV in Fig. 13.

Fig. 15 is an enlarged fragmentary view of the portion of the mat enclosed within the broken line circle indicated by the reference XV in Fig. 1.

I claim:

The ornamental design for a floor mat for automobiles and the like, as shown.
